UNITED STATES PATENT OFFICE

DAVID R. BOWEN, OF ANSONIA, AND CARL F. SCHNUCK, OF NEW HAVEN, CONNECTICUT, ASSIGNORS, BY MESNE ASSIGNMENTS, TO FARRELL-BIRMINGHAM COMPANY, INCORPORATED, OF ANSONIA, CONNECTICUT, A CORPORATION OF CONNECTICUT

MACHINE FOR MIXING OR MASTICATING RUBBER AND LIKE MATERIAL

Application filed January 17, 1927. Serial No. 161,624.

This invention relates to machines for treating rubber and similar material, and has particular reference to machines for masticating, kneading or mixing rubber, 5 which is to be used for various industrial purposes. The machine shown may be advantageously used, for example, in reducing to a smooth, uniform and plastic mass, a mixture of rubber chunks of various sizes, 10 pieces of tar and filling or coloring material in powdered form, although it will be obvious that the invention is not limited to this particular use but will be applicable to machines for mixing or masticating various 15 kinds of plastic material.

This application is a continuation in part of our application Serial No. 507,961 filed October 15, 1921, which has matured into Patent No. 1,623,159, April 5, 1927.

20 Machines of this character are generally provided with a mixing chamber and a rotary power driven element mounted in the chamber for mixing or masticating the charge by pressing and smearing it against the chamber walls while at the same time working the charge around the periphery of the chamber and propelling it from one end to the other. In some machines of this 25 character difficulty has been encountered by reason of the slippage of the mass on the interior surface of the wall of the mixing chamber, for it will be obvious that if the mass slides freely on the chamber wall and moves around with the rotor without the latter doing much effective work thereon in the way of forcing powder into the rubber, or smearing the latter against the chamber wall, the length of time required to reduce the charge to the proper plastic state will be increased. It has also been discovered that if the chamber wall is provided with projections extending toward the rotor so that the charge will be given a wedging or pressing action between the rotor blades and these 40 projections, in addition to the smearing action against the chamber wall, the efficiency of the machine will be further increased.

45 One object of this invention is to provide a mixer of such construction that the charge will be effectively squeezed against the wall

of the chamber as well as worked and smeared out thereover, so as to effectively mix and knead it, and in addition, will be prevented from slipping freely about the chamber ahead of the rotor.

55 Another object of the invention is to provide a rubber mixer wherein the mass of rubber which is being operated upon will be repeatedly squeezed or ground against the chamber wall by the rotor at a plurality of 60 places longitudinally of the chamber.

65 Another object of the invention is to construct a rubber masticating machine of improved character and increased efficiency by providing for a varied amount of clearance at a number of places along the length of the chamber, between the blades of the rotor and the chamber wall.

70 A still further object of the invention is to provide for an extensive wedging or squeezing action of the charge between the blade and the chamber wall, at a plurality of places throughout the length of the chamber and rotor.

75 To these and other ends, the invention consists in the novel features and combination of parts to be hereinafter described and claimed.

In the accompanying drawings:

Fig. 1 is a vertical central section of a 80 rubber masticating machine, embodying the principles of our invention;

Fig. 2 is a sectional view on line 2—2 of Fig. 1;

Fig. 3 is a sectional view of the mixing chamber shown in Fig. 2, with the rotor 85 omitted;

Fig. 4 is a view similar to Fig. 3, but showing a modified form of the invention;

Fig. 5 is a sectional view of a mixing chamber, showing a further modified form of the 90 invention;

Fig. 6 is a view similar to Fig. 5, with the rotor omitted;

Fig. 7 is a view similar to Fig. 6, showing 95 a further modification;

Fig. 8 is a sectional view on line 8—8 of Fig. 7, but including the rotor;

Fig. 9 is a view of a modified form of the rotor shown in Fig. 1.

In order to illustrate the principles of the 100

invention, we have shown a rubber working machine having a horizontal mixing chamber 20 of generally cylindrical shape, mounted between suitable standards or end frames 21, having heads 22 which close the cylinders at the respective ends. The end frames and the body portion of the cylinder may be conveniently interconnected by the bolts 23. A rotary mixing element 24 is provided within the mixing chamber upon a horizontal shaft 25, with bearings 26 and 27 in the respective cylinder heads. Suitable packing glands 28 and 29 may be provided to prevent any leakage of portions of the charge about the ends 15 of the rotor shaft.

That portion of the rotor within the chamber is provided with a plurality of blades 30 for mixing or kneading the material which, in this instance, is charged into the cylinder through the end charging opening or hopper 31. As illustrated in Fig. 1, these blades are arranged so that the material in one end of the chamber is picked up and while being forcibly pressed and worked against the inner periphery of the chamber wall, is moved toward and past the center of the chamber and into the other end portion thereof, while simultaneously the material in the last named end is similarly worked against the periphery 25 of the chamber and moved in a reverse direction. The blades as shown in this figure extend substantially throughout the length of the rotor, so that the material is moved from one end of the chamber to a point adjacent the opposite end where it is picked up by the following blade.

The working chamber of the machine shown, is divided longitudinally into sections, one section 32 being fixed relatively to the heads, and the other section 33 being hinged or pivoted to the first at 34, and designed to be swung about its hinge in such a manner as to provide for the discharge of the material at the bottom of the chamber. A suitable counter weight 35 is provided to normally maintain the chamber in open position. When the chamber is closed, it may be located in closed position by suitable latching and locking means designated generally by the numeral 36, and which it is unnecessary to describe with particularity in this application, as no claim is made specifically thereto.

It has sometimes occurred that when it has been attempted to masticate a batch of rubber in a chamber having a smooth wall, slipping of the charge about the chamber in advance of the rotor occurs to such an extent that an effective smearing action upon the chamber walls is not obtained. We have discovered, however, that where the interior surface or face of the chamber is properly formed, this slipping action can be prevented and there also can be obtained an effective squeezing or crunching action of the mass of material between the rotor and chamber at a

number of points along the length and upon the periphery of the chamber, which will greatly increase the efficiency of the machine and correspondingly shorten the time required for the mixing operation. To this end, in the embodiment of our invention shown in Figs. 1 to 3, we have shown a chamber having corrugations upon the interior surface of the wall thereof. These corrugations are formed by a plurality of generally transversely extending ribs 37, which project inwardly toward the rotor and between which lie corresponding grooves or valleys 38. In the form shown in this figure, the plane of the ribs and valleys is substantially transverse to the rotor axis. As the ribs or ridges 37 project inwardly toward the rotor, the clearance space between the rotor blades and the chamber wall will be substantially reduced at the points where these ribs are formed, the grooves, however, being relatively shallow so that there will be no tendency for parts of the material to be caught and remain stationary therein, and avoid being mixed with the rest of the charge. The ribs have rounded outer surfaces so that a substantial part of these surfaces will be opposed to the rotor blades. It will be apparent that the mass of the material when it is being carried from one end of the chamber to the other in its passage around the chamber, will, when it is brought into contact with one of the protruding ribs or ridges, be squeezed or pressed and crunched against the ridge by the rotor blades with the result that the rubber mass will be effectively spread out and squeezed, and the powdered coloring matter effectively ground and pressed into it, the particles being so thoroughly redistributed that a homogeneous, plastic mass is obtained in a relatively short time. Moreover, as the grooves extend in a transverse direction relatively to the rotor blades, there will be no tendency for the blades to merely work the material around the grooves without forcing it lengthwise of the chamber. In addition, as the material is being moved lengthwise of the chamber, the ribs will oppose and prevent any tendency of the material to slip about the inner surface of the chamber, and an intensive wedging action will be produced between the rotor and the inwardly projecting ribs, which catch the material and hold it back to some extent so that the rotor blades may exert a relatively strong pressure upon it. Moreover, the rounded protruding ribs are not so apt to become worn down, as would smaller and more minute and sharper projections upon the active surface of the chamber.

It is apparent that throughout the length of the chamber the clearance between the tip of the rotor blades and the chamber wall will be constantly varied, as the blade advances. This constantly varying clearance provides for a grinding action between the tip of the

blade and the chamber wall, and results in a redistribution of the particles in a much more thorough and efficient manner than when the clearance space between the relatively movable and stationary parts is constant. In the latter case, the charge would have a tendency to assume a certain shape and position in a solid mass in front of the blade and be propelled around by it without the proper kneading and smearing action.

In Fig. 4 we have shown another modification of our invention, in which the ribs 39 and the valleys 40 are inclined relatively to the axis of the chamber. In this case, however, all of the ribs or ridges extend substantially in the same direction and are all more or less transverse to the rotor blade so that a similar intensive wedging action of the material between the rotor blade and the chamber wall is produced, and likewise, the slippage of the material about the chamber is effectively prevented. In Figs. 5 and 6 of the drawings, we have shown a further modification wherein the mixing chamber is provided with an intermediate extrusion rib 41. In this case, the rotor is provided with relatively short blades 42, extending from the ends of the chamber to the extrusion rib, so that the charge is moved from one end of the chamber to and past the extrusion rib, and thrown over into the other end where it is picked up by another blade and moved in the reverse direction. In this case, the blades are staggered upon the rotor relatively to each other, so that the material released by one blade will be immediately picked up and acted upon by the following blade. Each end of the chamber, as shown in Figs. 5 and 6, is provided with a plurality of annular ribs 43 and valleys 44, which extend in a generally transverse direction around the chamber, which in this instance, is likewise of cylindrical shape, the direction of the ribs and grooves being inclined to some extent, however, relatively to the axis of the rotor. Moreover, the ribs in one end of the chamber are inclined oppositely to those in the other end, so that they will lie at substantially the same angle relatively to the movement of the material, as it will be apparent that in this instance, the material in one end of the chamber is moved in a direction opposite to that in the other end. In Figs. 7 and 8, of the drawings, is shown a further modification wherein the mixing chamber is provided in addition to the extrusion rib 45, with a plurality of ribs 49 extending longitudinally thereof parallel to the chamber axis, and a number of relatively large projecting ridges 50, extending generally around the chamber wall but not forming complete circular ribs. Each rib 50, as shown, is substantially semi-circular in form and is inclined to some extent relatively to the chamber axis. It will be apparent that in this instance, the tend-

ency of the material to slip upon the chamber wall is opposed both in longitudinal and circumferential directions, the result being a very effective mixing and kneading action, as has been heretofore described.

In Fig. 9 of the drawings, we have shown a rotor which is a modification of that shown in Fig. 1. In this instance, the blades 51 do not extend throughout the length of the chamber, but terminate at substantially the central portion thereof, so that the material is released by the blade in one end of the chamber to be picked up by the following blade in the opposite end of the chamber. The blades, in this instance, are arranged in staggered relation upon the rotor. It will be understood, of course, that the annular extrusion rib shown in Figs. 5, 6 and 7, of the drawings, may or may not be used with any of the forms of the projecting or protruding ridges upon the chamber walls. It will also be apparent that in all forms of the invention shown, there is provided a masticating and mixing device which will produce a peculiarly effective and intensive wedging action upon the batch of material being treated, which will result in a rapid reduction of the charge to a homogeneous plastic mass.

While we have shown and described some preferred embodiments of our invention, it will be understood that it is not to be limited to the forms shown, but is capable of modification and variation within the spirit of the invention and within the scope of the appended claims.

What we claim is:

1. A rubber mixing machine comprising a chamber, a bladed rotor to work the material back and forth within the chamber, said chamber having ribs on its inner surface projecting toward the rotor, and said ribs extending about the chamber in a direction generally transverse to the rotor axis and being disposed opposite the rotor blades.
2. A rubber mixing machine comprising a chamber having a curved inner wall, and a rotor having blades to work the material lengthwise of the chamber in opposite directions and smear it upon the chamber wall, said wall having rounded, transversely extending, inwardly projecting ribs upon its inner surface, opposite the rotor blades.
3. A rubber mixing machine comprising a chamber, and a bladed rotor to work the material back and forth within said chamber, and elongated ribs on the inner surface of the chamber wall opposite the blades of the rotor and extending generally transversely to the rotor axis, the rotor blades being arranged to work the material over said ribs lengthwise of the chamber to bring about an intensive wedging action between the ribs and the rotor blades.
4. A rubber mixing machine comprising a chamber, and a bladed rotor to work the

material back and forth therein, said chamber comprising a single cylinder having upon its inner surface elongated ribs projecting toward the rotor and extending in a generally transverse direction across the rotor blades, and said rotor blades being arranged to work the material over said ribs lengthwise of the chamber to bring about an intensive wedging action between the ribs and the rotor blades.

5. A rubber mixing machine comprising a chamber having a transversely curved and corrugated inner surface, and a rotor in the chamber having blades extending across said corrugations and adapted to work the material back and forth in the chamber over said corrugations.

6. A rubber mixing machine having a cylindrical chamber, said chamber having relatively shallow corrugations on its inner surface extending in a direction generally transverse to its axis, and a rotor in the chamber having blades extending across said corrugations adapted to work the material back and forth over said corrugations.

7. A rubber mixing machine having a chamber of cylindrical shape, a bladed rotor therein, and ribs upon the inner wall of the chamber opposite the rotor blades and extending generally transversely of the chamber axis and projecting toward the rotor, and said rotor being arranged to work the charge over said ribs lengthwise of the chamber in both directions.

8. A rubber mixing machine having a chamber with a substantially continuous transversely curved inner surface, a bladed rotor to work the material back and forth upon said surface, and elongated inwardly protruding members formed upon the surface opposite an intermediate portion of the rotor blades and extending generally transversely of the chamber.

9. A rubber mixing machine having a mixing chamber, and a bladed rotor operatively mounted therein to work the material lengthwise thereof in opposite directions, said chamber having, upon its working face, elongated, generally transversely extending, inwardly projecting members to vary the clearance between the working face and the rotor blades.

10. A rubber mixing machine having a mixing chamber with a curved working surface, and a bladed rotor operatively mounted within the chamber to work the material lengthwise thereof and smear it upon the chamber walls, and inwardly protruding members extending peripherally along the inner curved surface of the chamber wall in a direction generally transverse to the rotor axis to vary the clearance between the chamber wall and the rotor blades, said rotor blades working the material longitudinally of the chamber in both directions.

11. A rubber working machine having a mixing chamber and a rotor operatively mounted therein, an intermediate extrusion rib upon the chamber wall, and said chamber being provided on its working face on one side of said rib with elongated generally transversely extending members to vary the clearance between the working face of the chamber and the rotor.

12. A rubber mixing machine having a chamber provided with an intermediate extrusion rib, a bladed rotor operatively mounted in the chamber to work the material past said rib in opposite directions, and elongated protrusions upon the chamber wall on each side of the rib and extending generally transversely of the chamber across which the material is worked in its passage toward the intermediate rib.

In witness whereof, we have hereunto set our hands, this 13th day of January, 1927.

DAVID R. BOWEN.
